UNITED STATES PATENT OFFICE.

MAX E. SCHENKE, OF BROOKLYN, NEW YORK.

DESIGN FOR A SLIPPER.

46,323.

Specification for Design.

Patented Aug. 25, 1914.

Application filed June 15, 1914. Serial No. 845,319. Term of patent 3½ years.

To all whom it may concern:

Be it known that I, MAX E. SCHENKE, a subject of the German Emperor, residing at Brooklyn, in the county of Kings and State of New York, have invented a new, original, and ornamental Design for Slippers, of which the following is a specification, reference being had to the accompanying drawings, forming part thereof.

I claim:

The ornamental design for a slipper as shown.

In testimony whereof I affix my signature in the presence of two witnesses.

MAX E. SCHENKE.
